UNITED STATES PATENT OFFICE.

FRED FARRELL, OF CHICAGO, ILLINOIS, ASSIGNOR TO ELECTRICAL ENGINEERS EQUIPMENT CO., OF CHICAGO, ILLINOIS, A CORPORATION OF ILLINOIS.

SWITCH.

Application filed October 31, 1924. Serial No. 746,969.

My invention relates to electric switches of the outdoor type. Such switches being exposed to the weather are subject to accumulations of sleet and ice which tend to clog 5 the contacts and make it difficult to close the switch. When one of the switch contacts is a split contact or socket the ice or sleet may jam the same and prevent proper closing of the switch. Also, the split or socket contact 10 may be damaged by such clogging with ice or sleet in attempting to close the switch.

In the case of a stud contact it is easy to cut or scrape the ice or sleet coating off because it drops off externally, but that is not 15 true in the case of a split or socket contact which is usually employed in combination with a stud contact.

I have observed that if the two contacts, that is, the split or socket contact and the 20 stud contact, are held at all times in a horizontal position and are brought into engagement with each other through a substantially horizontal motion, the split or socket contact may be covered with an overhanging hood 25 which protects it from a deposit of sleet or ice. The stud contact, even if exposed to the weather, is easily cleaned by the scraping motion of the split or socket contact along the sides of the same. My invention relates to 30 this class of switches where the contacts are brought into engagement by a motion which will permit the socket contact to be held at all stages of its motion in such a position, that is, substantially horizontally, so that it may 35 be protected by a projecting or overhanging sleet hood.

I am aware that it is old to bring the two contacts into engagement by swinging one of them in a horizontal plane, the opening or 40 rupturing distance being secured by movement of an arm about a vertical pivot, but that is not satisfactory. The stud contact then has its flat side facing upwardly with the possibility of accumulating a relatively 45 large amount of sleet or ice upon its top side, which unbalances the action of the contact and is more difficult to remove. I am also aware of switches having contacts guided in fixed horizontal guides for rectilinear motion. It is difficult to secure the required rupturing without too great mechanical complication and friction.

According to my invention, I dispose the contacts in a vertical plane and bring them

into engagement by a motion which may best 55 be described as a plunging motion produced through a linkage involving two links pivoted to a third link or arm.

In the preferred form of the invention 60 these links are non-parallel for the purpose of changing motion from a strictly parallel motion to a compound motion, which provides that the movable contacts shall stand when the switch is opened in an inclined 65 position, and shall approach more nearly a horizontal position as the switch is closed. This permits the open position to provide greater rupturing space and, in the preferred embodiment, permits the movable contacts to be better protected from the weather.

I provide according to my invention two 70 links pivoted at one end at separate points upon an arm and pivoted at their other ends at separate points on a rigid frame member. In the preferred embodiment of the invention the rigid frame member is movable and supports the movable contact member, while the opposite end of the arm is pivoted to a 75 stationary support and hence is stationary. The relative motion between the opposite 80 ends of the linkage, regardless of which end of the linkage is free, is highly useful for operating the switch contact.

In the preferred embodiment the non-parallel links are pivoted upon the arm at their 85 converging ends and to the frame at their diverging ends, the result being a greater spacing of the pivots on the frame member than on the arm member. The frame member which is movable carries the socket contact and also carries a sleet hood, but the 90 invention is not to be limited to this specific arrangement.

One great advantage of this linkage is that 95 for a given length of switch arm the separation of the contacts is relatively great and the linkage which corresponds to the blade of the ordinary switch pulls up out of the way in the vertical plane of the line conductor.

A specific advantage of the preferred embodiment is the guiding of the movable contact upon the top of the swinging operating insulator. The movable contact, with its sleet hood, is constrained both by the linkage and by the operating insulator which is pivoted to the contact. The movable insulator also relieves the linkage of the weight of the contact and the hood, so that the linkage may 100 105

be made relatively much lighter than would be required if the linkage alone were called upon to support the movable contact.

To acquaint those skilled in the art with the manner of constructing and practicing the present invention, I shall in connection with the accompanying drawings, describe a specific embodiment of the same.

In the drawings:—

10 Fig. 1 is a side elevation of the separable contacts showing the means employed for mounting and adjusting the hood, and the positions of the hood when the contacts are in and out of engagement in solid and broken 15 lines, respectively;

Fig. 2 is a fragmentary side elevation of the separable contact means showing the manner in which the hood is mounted on the rocking member;

20 Figs. 3 and 4 are sectional views taken on lines 3—3, and 4—4, respectively, of Fig. 2; and

Fig. 5 is a rear elevation of the hood.

The hood 7 has a side wall 8 from the margin of which a wall 9 extends laterally and closes the back and top of the hood. The side 25 8 projects forwardly beyond the blade means 14 and wall 9 is turned down a short distance along the forward margin thereof at 10 and moves over stud 15 ahead of blade 14 and offers maximum protection for the stud, blades and blade mounting when the switch is closed. The back is turned out at 11 and the bottom 30 12 is turned down at 13 to form a suitable opening 20 with the back through which the flat flexible conductors 24 may be led for connection with blades 14. The opposite end of the bottom 12 is turned up at 21, the space between this upturned end 21 and the down-turned end 10 forms an opening 22 through which the stud 15, which is secured to the fixed member 61, is adapted to extend for contact with blades 14. The hood 7 forms a frame member upon which the movable contact 14, in this case is mounted, and to which the divergent ends of the links 50 and 51 are pivoted.

One side of hood 7 is open at 25 to permit mounting the blades in the hood. This open 50 side 25 is closed by a cover 26. Projecting laterally from the inner side of cover 26 are lugs or flanges 27 which cooperate with the back, top, bottom, downturned and upturned ends to position the cover on the open side 25 of the hood 7. The cover and hood are secured together at their rear end by bolts 28, one arranged above the other and an additional bolt 29 to bind together the forward end of the hood and cover. Suitable recesses 55 30 are provided in the side 8 and the cover 26 in order that heads of bolts 28 and 29 may be flush with the outer surfaces of the side and cover respectively. The side 8 and the cover 26 also have integral with their inner surfaces projecting pins 31 on which are mount-

ed springs which are used to help align the blades 14.

Integral with the bottom 12 is a lug 32 which is pivotally secured to the rocking member 34 by means of the pin 33. The 70 pin 33 is headed at both ends to keep it in position.

Integral with the back 9 and centrally located at the lower portion thereof, is a bifurcated lug 40 to which is pivotally connected 75 a link 50 by means of the pin 35. A bifurcated lug 41 is integral with the downturned portion 13 of the bottom 12 and is in the same vertical plane with the bifurcated lug 40. To lug 41, link 51 is pivotally connected by means of pin 36. Both pins 35 and 36 are headed at both ends. The opposite end of link 50 is pivotally connected to one end of arm 52 by means of pin 37. Link 51 is also pivotally connected to link 52 by means 80 of pin 38 at a point below that to which arm 50 is connected. The lower end of arm 52 is pivotally connected to a fixed member 63 by means of pin 39. Connecting pins 37, 38 and 39 all are headed at both ends to prevent 85 their working out of position. The flexible conductors which are preferably braided copper ribbons 24 pass through the opening in the hood 20 and are connected to the blades 14. These conductors lie on each 90 side of the links connecting the hood with the fixed member 63 and are fastened to them at regular intervals by suitable fastening means. The free ends of the conductors 24 are secured to a base member 67 the fixed insulator 63 by a clamping plate 64 which has a curved guide at 65 at its forward end for controlling the flexing of the ribbons 24. The plate 66 also has an integral lug 66 to which 95 are pivoted the rear ends of arm 52. The line conductor 68 is provided with a socket terminal 55 which is bolted to the base plate 67 over the ribbons 24. The base plate 67 has an integral extension reaching out beyond the terminal 55. It is adapted to take the mechanical stress of the conductor 68 off of the terminal. To this end the conductor 68 is 100 clamped to said extension 69 by a U-bolt 70.

The conductor 71 is connected to the stationary terminal stud 15 in a similar manner. 115 In this case the conductor is connected electrically through a socket terminal 72 which is bolted to the lower end of the stud 15. The stud 15 has a laterally extending lug 73 and a U-bolt 74 for gripping the conductor 71 120 beyond the terminal 73.

When the switch is open, the rocking member, hood, and links will take the positions 62', 7', 50', 51' and 52' which are indicated by the dotted lines of Fig. 1. In this position 125 the hood covers the blade mechanism in a manner which will prevent sleet, snow, or rain from getting at it. If now the rocking member is swung over so that contact is made between the blades 14 and the clip 15, the hood 130

again will afford maximum protection to the blade mechanism from the elements above mentioned. Hence, it is seen, that the hood will always adjust itself to give maximum protection to the blade mechanism whether it is in or out of contact. Furthermore, because of the arrangement of the links, the hood is actuated at all times by a uniformly constrained positive motion. This permits it to operate smoothly, thereby eliminating any jarring which would tend to disalign the blade mechanism and prevent them from functioning properly.

I do not intend to be limited to the details of construction of the particular embodiment shown, but intend that all such modifications and variations as will suggest themselves to one skilled in the art and coming within the spirit of my invention be included within the 20 terms of the appended claims.

I claim:—

1. In combination, a protecting hood, the back and bottom of said hood having lugs integral therewith, said lugs being in substantially the same vertical plane and located at the lower and back portions of the back and bottom respectively, and linkage means connected to said lugs.

2. In a switch, a fixed member, a base plate having an integral extension secured thereto, flexible conductors secured to said plate by guide clamping means and by a socket having a conductor securely fastened therein, said conductor being also secured to the integral extension of said base plate by suitable bolt means.

3. In a switch, in combination, a rocking member having a lug secured thereon, a protecting hood having a lug pivotally connected to said lug, a pair of lugs on said hood, and links pivotally connected to said lugs for imparting an independent angular motion to said hood.

4. In a switch, in combination, a fixed member, a rocking member, a protecting hood pivotally mounted on said rocking member, flexible conductor means secured to said fixed member, a link member pivotally mounted on said fixed member, a pair of link members pivotally connected to said protecting hood, the opposite ends of which are pivotally connected to the link member connected to said fixed member, said flexible conductor means being looped over the connection between the link member connected to the fixed member and the link members connected to the protecting hood.

5. In a switch, in combination, a fixed member with contact means secured thereto, a second member, a rocking member fixed therebetween, a hood having contact means fastened therein and pivotally mounted on said rocking member, link mechanism for actuating said hood, said link mechanism comprising a pair of links pivotally secured to said

hood, and an arm pivotally connected to said fixed member and to said links.

6. In a switch, in combination, a fixed member with contact means secured thereto, a second member, a rocking member fixed therebetween, a hood having contact means fastened therein and pivotally connected to said rocking member, link mechanism for actuating said hood, said link mechanism comprising a pair of links pivotally secured to said hood, and an arm pivotally connected to said fixed member and to said links, said hood being actuated by said links.

7. In a switch, a socket contact, a stud contact, said contacts being adapted to be brought into and out of engagement by substantially rectilinear motion, an insulator upon which one of said contacts is rigidly mounted, a second insulator, a collapsible linkage comprising a pair of arms, and a single arm pivoted to said pair of arms, said linkage bearing the movable contact at one extremity and having pivotal connection with the second insulator, and means for collapsing and expanding said linkage.

8. In a switch, in combination, a fixed member having contact means thereon, a rocking member having contact means thereon adapted for cooperation with the contact means on said fixed member, a protecting hood over one of said contact means, and link mechanism for actuating said hood comprising a pair of links pivotally connected to said hood and to a pivotally mounted arm member.

9. In a switch, in combination, an insulating member having contact means thereon, a second insulating member having contact means thereon, means for bringing said contact means into and out of engagement, said means comprising a pair of links pivotally connected to one of said contact means at one end and to a pivotally mounted arm at the opposite end.

10. In a switch, a contact operating linkage comprising the combination of a frame member, an arm member, a pair of non-parallel links having their convergent ends pivoted at separate points upon the arm member, and having their divergent ends pivoted at separate points upon the frame member, a movable contact upon one of the members, a pivotal support for the other member, and means for operating said linkage to move said movable contact.

11. In a switch, a contact operating linkage comprising the combination of a frame member, an arm member, a pair of non-parallel links having their convergent ends pivoted at separate points upon the arm member, and having their divergent ends pivoted at separate points upon the frame member, a movable contact upon one of the members, a pivotal support for the other member, and means for operating said linkage to move said movable contact, a stationary contact adapted to

be engaged by the movable contact, and a sleet hood for one of said contacts.

12. In a switch, a contact operating linkage comprising a frame member, an arm member, a pair of links pivoted at one end at separate points upon the frame member and pivoted at their other end at separate points upon the arm member, a movable contact carried upon one of the members, a pivotal support for the other member, and a movable insulator pivoted to one of said members to operate said linkage to move said movable contact.

13. In combination, a swinging insulator, a sleet hood pivoted on said insulator, a contact mounted in the hood and supported thereby, a linkage connected to said hood and controlling the angular position thereof about said pivot, a second insulator bearing a cooperating contact, an arcing horn for said second insulator and an arcing horn cooperating with the first arcing horn and mounted on the first insulator below said pivot.

14. In combination, an insulator pivotally mounted about its lower end, a sleet hood piv-

oted directly on the upper end of the insulator, said hood being open at its front and closed at top, back and side, a contact mounted in the hood and a pair of controlling links pivoted to said hood and controlling the position thereof.

15. In combination, a sleet hood open at its front and closed at top, back and sides, a contact mounted on the inside of the hood and movable angularly therewith and a pair of controlling links pivoted to said hood and controlling the angular position of said hood and of said contacts.

16. In combination, a sleet hood open at its front and closed at top, back and sides, a contact mounted on the inside of the hood and movable angularly therewith and a pair of controlling links pivoted to said hood and controlling the angular position of said hood and of said contacts, and a single link pivoted to both of said links and to a stationary pivot.

In witness whereof, I hereunto subscribe my name this 28th day of October, 1924.

FRED FARRELL.
